(No Model.)

P. M. GUNDLACH.

GRAIN DRILL.

No. 351,047.

Patented Oct. 19, 1886.

UNITED STATES PATENT OFFICE.

PHILIP M. GUNDLACH, OF BELLEVILLE, ILLINOIS.

GRAIN-DRILL.

SPECIFICATION forming part of Letters Patent No. 351,047, dated October 19, 1886.

Application filed September 7, 1881. Serial No. 41,522. (No model.)

To all whom it may concern:

Be it known that I, PHILIP M. GUNDLACH, a citizen of the United States, and a resident of Belleville, in the county of St. Clair and State of Illinois, have invented certain new useful Improvements in Grain-Drills, of which the following is a specification.

My invention consists, first, in the provision of a removable frame to which supplementary flukes are attached, so that they can be detached from the machine when they are not required, and which frame can be used to receive one set of the main flukes in setting them zigzag; second, in the combination, with the half-hooks to which the drag-bars are attached, of a pivoted locking plate or latch for holding the parts in engagement, as will hereinafter more fully appear; third, in the provision of the thimble-skein formed with open-ended slots instead of holes, the purpose being to avoid the use of cores in casting, as will hereinafter more fully appear.

In the drawings, Figure 1 is a vertical section of the grain-drill, showing the general arrangement of parts. Fig. 2 is a transverse section illustrating the mode of adjusting the vertical cut-off plate. Fig. 3 is a plan view, and Fig. 4 a perspective view, of the thimble-skein. Fig. 5 is a detail side elevation of the grain-feeding device. Fig. 6 is a detail plan of same. Fig. 7 is a detail side view of the hinged plate or tongue. Fig. 8 is a detail front view of the same. Fig. 9 is a detail view illustrating the latch mechanism, &c., for holding the drag-bars in position upon their half-hooks. Fig. 10 is a detail side view of the feed-cylinder.

A represents the grain-box, supported on a suitable frame mounted on wheels, in the usual manner, and having attached to its bottom a series of independent housings or bearings, B, for the feed-cylinders C, which are operated by a single transverse shaft, c, that receives its motion from a set of gearing (not shown) operated by one of the ground-wheels. The motion communicated to the feed-cylinders is a forward one, so that the feed will be an "overshot" one instead of an "undershot," as usual to ordinary grain-drills. The grain-grooves c' in the feed-cylinder are made straight or parallel with the axis of the cylinder, so that in connection with the bevel or

sloping ended tongue c² the action will be to discharge the grain in a gradual manner. The bevel or sloping ended tongue or plate c² is 55 pivoted in the housing B and rests against the forward face of the feed-cylinder, the purpose being to hold the grain in the grain-grooves until the proper time to discharge the same.

c³ is a horizontally-sliding cut-off plate for 60 regulating the amount of grain fed by the feed-cylinder. This cut-off plate is arranged immediately over the feed-cylinder and between it and the feed-opening. The advantage of this construction is that it permits the cut-off 65 plate c³ to be made stationary and obviates the necessity of the turning of the same with the feed-cylinder, which is a very objectionable feature in the ordinary cut-offs used in grain-drills.

D are vertically-sliding plates arranged at 70 each seed-opening, for the purpose of adjusting the seed-opening to suit different sizes of grain, and also to regulate the quantity discharged, when desired. These plates are vertically-adjustable in the following manner:

D' is a horizontally-sliding plate, provided with a series of inclined slots, d, which receive pins or studs d' upon the plate D, so that by a horizontal movement of the plate D' by its operating-lever D² all the vertical plates D will be equally and simultaneously adjusted.

E are a set of supplemental flukes arranged between the main flukes E', and attached to a frame, F, made removable from the main frame 85 of the drill, the object being to allow the supplemental flukes E and frame F to be detached from the drill-frame when not required for use.

The frame F is provided with a sufficient 90 number of attaching-hooks to permit of each alternate one of the main flukes E' being attached to it by their drag-bars in setting to a zigzag.

The mode of attachment of the drag-bars E² 95 of the flukes, so as to render them readily removable, is as follows:

e are a series of half hooks or staples, having their pivots e' pointing in one direction, so that the forked portion of the drag-bars can 100 be readily slipped onto and off them. When in engagement, the parts are locked in position by a pivoted latch or dog, e², in manner clearly indicated in Fig. 9.

G is the thimble-skein, formed with ears g, as usual, for attachment to the frame of the drill, and these ears, instead of having holes for the attaching strap or bolts, are provided 5 with open-ended slots g', arranged in reversed directions, as indicated in Fig. 3, the purpose being to avoid the use of cores in casting the same.

I am aware that prior to my invention an 10 oscillating drag-rail has been used in grain-drills, attached below the drill-frame and forming a permanent part of the drill proper. I am also aware that supplementary flukes or shovels have been so attached as to come be- 15 tween and in the rear of the ordinary flukes of a grain-drill. I therefore do not claim either of such combinations, broadly; but

What I do claim as my invention, and de- 20 scribe to secure by Letters Patent, is—

1. In a grain-drill, the removable frame F,

detachably secured to the main frame of a grain-drill, and provided with a series of supplementary flukes to lie between the main flukes of the drill, essentially as and for the purpose set forth.

2. In a grain-drill, the combination of the drag-bar E' with the half hooks or staples e and locking-latch e², substantially as described, and for the purpose set forth.

3. The thimble-skein G, having attaching- 30 lugs g, provided with open-ended slots g', as described, and for the purpose set forth.

In testimony whereof witness my hand at Belleville, Illinois, the 27th day of August, 1881.

PH. M. GUNDLACH.

In presence of—

M. F. SIEFERT,
GUSTAVUS NEUMANN.
